GRATING

Mark M. Stone, Highland Park, Ill., assignor to Metalex Corporation, Libertyville, Ill., a corporation of Illinois

Filed Feb. 15, 1968, Ser. No. 10,588

Term of patent 14 years

(Cl. D13—1)

FIGURE 1 is a plan view of the grating design in accordance with this invention, showing the ornamental general shape of the grating and the ornamental repetitive pattern thereof;

FIGURE 2 is an enlarged plan view of the grating design of FIGURE 1, showing the ornamental repetitive pattern thereof in substantial detail;

FIGURE 3 is an elevational front view of the grating illustrated in FIGURE 2;

FIGURE 4 is an elevational end view of the grating illustrated in FIGURE 2;

FIGURE 5 is a removed sectional view of the bond portion of the grating, taken along the line 5—5 in FIGURE 4;

FIGURE 6 is an enlarged sectional view of the bond portion of the grating taken along the line 6—6 in FIGURE 5; and

FIGURE 7 is an enlarged cross-sectional view of the grating, taken along the line 7—7 in FIGURE 5.

I claim:

The ornamental design for a grating, substantially as shown and described.
